ATTACHMENT PLUG RECEPTACLE

Arthur C. Gaynor, Stratford, Conn.

Application July 16, 1931, Serial No. 551,075

7 Claims. (Cl. 173—330)

This invention relates to attachment plug receptacles, particularly those adapted to be mounted in an outlet box or the like, and is an improvement on the receptacle shown in my Patent 1,719,363, granted July 2, 1929.

5 In my aforesaid patent I have disclosed a double or duplex receptacle with a body of one piece construction open at the back with longitudinal apertures to receive contact members on edge, and having side wall openings through which a laterally offset terminal portion of the contact member extends. However, I depend upon a fibre or similar strip to cover the contact apertures and support the contacts therein, and provide a long strap for connecting the receptacle to an outlet box or the like, and hold the fibre strip in place.

10 It is an object of the present invention to provide a push plug receptacle body construction in which the molded insulation material of the body itself will substantially enclose the contact members and provide a solid body portion upon the back to take the load imposed upon the contacts, as when a push plug is moved through usual 15 prong slots.

20 It is another object of the present invention to accomplish what was just described, and in addition retain the advantages of having contact member terminal portions pass through side 25 wall openings, as disclosed in my aforesaid patent.

25 A feature of the present invention is the provision of novel outlet box connecting plates, which make it possible to dispense with the usual 30 connecting plate attaching screws.

35 Another feature is the provision of simple integral vertical fingers on the connecting plates entering suitable apertures in the receptacle body parts to locate the plates in the body, and also 40 serving to locate the body parts relative to each other.

45 A still further feature of the present invention is the provision of novel receptacle outlet box connecting plates fitting between upper and lower body parts, yet incapable of spreading or lever action between the two when a load is imposed upon the receptacle in a direction toward and from the outlet box or the like upon which the 50 plates are connected.

55 And yet another feature is the provision of a body construction which positively locates the contact members relative to the usual prong slots, yet allows free yielding movement of the prong receiving portions of the contacts, and which in

addition effects a considerable saving in the amount of material used and in material cost.

Another feature of the present invention is the provision of a molded two-part body with one-part having a single large cavity for the easy 5 reception of contact members and the other part having a rib entering the cavity to convert the one large cavity into two separate contact members.

In the drawing:

10 Figure 1 is a top plan view of the push plug receptacle.

Fig. 2 is a side elevation of the receptacle, in use, with the outlet box and flush plate in longitudinal section.

15 Fig. 3 is a longitudinal sectional view, taken on line 3—3 in Figs. 1 and 6.

Fig. 4 is a fragmentary end section, 4—4, in Fig. 3, and shows the end plate locating and connecting means.

20 Fig. 5 is a sectional view similar to Fig. 4, taken on line 5—5 in Fig. 3, at the other end of the receptacle, and in addition shows a portion of the contact member locating means.

Fig. 6 is a top plan view of the lower body part, 25 with contact members assembled therein.

Fig. 7 is a bottom plan view of the underside of the upper body member, with one end plate in place.

Fig. 8 is a perspective detail of the end plate. 30

Fig. 9 is a top plan view of a modified form of lower body part.

35 In the drawing there is illustrated a double or duplex push plug receptacle having a two-part body 10 comprising a lower body part or base portion 11 and an upper body part or cover portion 12 made of "Bakelite" or other suitable insulating material.

The lower body part 11 is made hollow or box like in shape, comprising side walls 13, end walls 40 14 and bottom 15, which form a contact receiving chamber 16. Two contact members 17 are

45 edgewise disposed in this one large open chamber, rather than in two small close fitting chambers as disclosed in my aforementioned application, thus making it possible for the assembler to freely manipulate the contacts at the time of assembly. Both of the side walls 13 are provided with an opening 18 which communicates with the chamber 16 and receives a laterally offset terminal portion 19 of the contact member 17 to locate it longitudinally.

50 The contact members 17, like the form disclosed in my aforesaid patent, are made from strip material with opposite ends 20 bent back upon them— 55

selves, at 21, to form contact fingers 22, for receiving usual push plug prongs. Upwardly projecting and outwardly bent ears 23 on the upper edge of the strips, as shown in Fig. 6, are provided to further guide the push plug prongs.

The laterally offset terminal portions 19 of each contact member 17 is tapped for either one or two terminal screws 24, and is formed so that the outer surface is preferably substantially parallel with the outer surface of the side walls 13. This contact member is adapted to be placed on its edge in the chamber 16 and is substantially supported by the bottom 15. Thus, when usual push plug prongs are forced into the contact fingers 22 of the contact member 17 the latter is substantially supported by the bottom 15.

In order to locate the contact members transversely within the chamber 16 there is provided a flat portion 25 adapted to engage the inner surface of the side wall 13 to prevent outward displacement, and a set of transversely extending ribs or beads 26 preferably made integral with the bottom 15 and adapted to engage the lower portion of the contact member to prevent inward displacement. The small one-point contact of the ribs 26 with the side of the looped portion of the contact member 17, near the center thereof, as shown in Figs. 5 and 6, makes it possible for the looped portion to yield considerably and adjust itself to any irregularity in the parallelism of the push plug prongs.

Although these ribs are of small height they effectively locate the contact member and prevent lateral displacement, and, at the same time, provide the large inner cavity or chambers 16 which makes it possible to freely manipulate the contact members 17 at the time of assembly, when moving the latter into place. In addition to this assembly advantage the hollowed body construction requires but little material and thereby a considerable saving in material cost is effected.

If desired, a central transversely extending rib or bead 27 may also be provided to engage the lower inside face of the terminal portion 19. This latter rib 27 alone may be used to prevent inward movement of the contact members 17, dispensing with the ribs 26, however, it is preferably provided along with the latter and serves mainly to prevent inward movement of the terminal portion 19, as an electrician pushes his screw driver against the head of the connecting or terminal screws 24, in tightening the latter. This rib is, like the ribs 26, made of but small height so that it does not make an obstruction to the operator's finger.

The upper body part or cover portion 12 is adapted to fit directly over the top of the base portion 11 to substantially enclose the contact members 17. It is provided with two pairs of parallel push plug prong receiving slots 28 adapted to overlie the looped contact fingers 22 of the contact members 17 when the cover is assembled to the base portion 11.

In its preferred form, the cover portion 12 is provided with downwardly projecting lugs 29 adapted to engage the inner side of the end walls 14 to locate it longitudinally and prevent displacement in this plane, and the sides 30 of these downturned lugs fit within a recess 31 in the base to locate it laterally.

Thus, after the contact members 17 are assembled to the base portion 11 it is merely necessary for the assembler to move the cover 12 toward the base portion while the lugs 29 enter

the recesses 31 to be located thereby and when moved fully into position the prong apertures 28 are sure to be in proper operating position over the looped contact fingers 22. The lugs 29 also serve to insulate the looped contact fingers 22 of the contacts 17 from connecting plates 32.

The under side of the cover portion 12 is also provided with transversely extending ribs 26a adapted to engage the top portion of the contact members to assist the ribs 26 of the lower or base portion 11 in locating the contact member and to prevent lateral or transverse displacement; and, at its center, it may be provided with a transversely extending rib 27a the ends of which engage the inside wall of the terminal portion 19 to assist the ribs 27 in the base portion to prevent transverse displacement of the contact member as an electrician applies tightening pressure to the terminal screw heads 24.

If desired, a longitudinally extending rib may be provided to further isolate the two contact members 17 from each other. In its present preferred form the present invention provides a longitudinally extending rib 33 on the lower body part 11, of substantially the same heights as the ribs 26 and 27, and a similar longitudinally extending rib 33a on the top body part 12 overlying rib 33 to form two separate contact chambers when the two body parts 11 and 12 are moved together.

If desired, the transverse rib 27 may be extended to form a large thin projection 47 on the base 11, as shown in Fig. 9, with side walls 27b to engage the inside of the terminal portion and prevent transverse shifting of the contact member 17. In addition, the ribs 26 may be extended to form the thin wide projections 48 with side walls 26b to engage the side of the looped members 22 to further locate it in place. The cavities, of slight depth, thus formed between the side walls 26b and/or 27b, and body side wall 13 also serve to effectively locate the contact members 17.

Projections similar to 47 and 48 on the lower body part, as shown in Fig. 9, may also be provided on the underside of the upper body part in place of the ribs 26a and 27a, as shown by dot-and-dash lines 49 in Fig. 7, and of any desired height. This form of the present invention is more easily molded and effectively locates the contact members in place relative to the prong slots 28. However, it does not allow the looped contact fingers 22 to yield to the same degree when the push plug prongs are bent or out parallel as does the preferred form, hereinbefore described.

With duplex receptacles it is customary to provide a substantially U-shaped strap extending down the side walls and across the bottom of the receptacle and having near its top a portion adapted to be connected to an outlet box or the like. These U-shaped straps are usually connected to the duplex receptacle with screw fastening means and in some cases with hollow or other type rivets. It is also a rather general practice to provide connecting means comprising small plates on each end of the receptacle which serve as a connecting medium. However, in this latter form it is also usual to provide a screw or rivet fastening means.

An important aspect of the present invention is the provision of connecting means which entirely dispenses with the usual screw and rivet fastening means for these plates. To this end the present invention provides outlet box con-

sheeting plates 32 having a section 34 with an elongated slot 35 for connection to the outlet box 36 and having a flat portion 37 adapted to fit within a slot or recess 38 in the top of the end walls 14 (or the slot 38 may be provided in the cover 12). Preferably this recess is made the same depth as the thickness of the plate 32 and is just wide enough to prevent skewing movement of the plate. Of particular importance, however, the plates are provided with a pair of vertically upwardly extending fingers 39 adapted to fit into a pair of suitable cooperating slots 40 in the cover 12 and are provided with a similar downwardly extending finger 41 adapted to fit within a three-walled aperture 42 in the end wall 14 of the base portion, the fourth wall being constituted by the face 43 of the lug 29.

These plates are assembled to the cover 12, as shown at the right side of Fig. 7, and the cover is then moved down toward the top of the base portion 11, after the contact members are assembled thereto, whereupon the lugs 29 ride into the apertures 31 and the vertical finger 41 portion of the plate moves into the aperture 42 of the lower body part 11, as shown in Fig. 3. After the two body parts are so assembled a tubular rivet 44 is passed through a substantially circular hole 45 in both the lower and upper body parts 11 and 12 until a square head portion of the tubular rivet 44 enters a suitable aperture in the base to prevent further vertical and turning movement and the upper end is then spun as at 46 to permanently secure the body parts together.

When the plates 32 are assembled between the two body parts and the latter are held together by the spun-over tubular rivet 44, movement of the body parts relative to each other in a horizontal plane as viewed in Fig. 3 is prevented by the rivet. In this condition, when vertical pressure is applied to the receptacle and transmitted through the plates 32 to the outlet box or the like, all tendencies of the plates to skew and thus separate the two body parts is avoided because of the fact that the ears 39 and 41 extend vertically into the two parts. Theoretically, if the ears 39 and 41 were weak enough to bend, pressure on the receptacle would cause the ears to act as a first-class lever moving about the division line between the two body parts as a pivot, and this would tend to shift the body parts horizontally. This horizontal shifting movement between the body parts would be prevented by the rivet to which the body parts would apply a shearing action.

However, in practice, the ears 39 and 41 extend into their respective body parts so far and fit the slots in which they are located so well that all skewing movement of the plate which might be transmitted into a separating movement between the body parts is avoided. In both of these connections it is within the scope of this invention to have the two fingers extended downwardly and one extend upwardly, or to provide the plates with but a single upwardly extending finger 39 and/or a single downwardly extending finger 41 to enter a suitable aperture in either the upper or lower body part respectively.

It is also within the scope of this invention to have the fingers 39 and 41 of the plate 32 serve to locate the cover 12 relative to the base 11 both longitudinally and transversely, for they may be made to serve in this very connection and thereby dispense with the downwardly extend-

ing cover lug 28 fitting within the aperture 34, if desired.

Other variations and modifications may be made within the scope of this invention and portions of the invention may be used without others.

Having thus described the invention, what is claimed as new and for which it is desired to obtain Letters Patent, is:

1. An attachment plug receptacle comprising a rectangular body of insulating material, having 10 side and end walls, recessed from its upper face to provide a single longitudinally extending contact receiving cavity; a pair of contacts adapted to stand on edge in said cavity at opposite side walls thereof; and a plurality of transversely extending raised beads, integral with the floor of the cavity, adapted to engage the sides of the contacts at spaced points and locate them relative to the side walls.

2. An attachment plug receptacle comprising 20 a rectangular body of insulating material, having side and end walls, recessed from its upper face to provide a single longitudinally extending contact receiving cavity; a pair of contact members adapted to stand on edge in said cavity and 25 each having a laterally offset terminal portion near its center adapted to fit into a cut-out portion of the adjacent side wall, to prevent longitudinal shifting of the contact members; and a plurality of transversely extending raised beads 30 integral with the floor of the cavity, adapted to engage sides of the contacts at spaced points for locating them relative to the side walls and preventing transverse shifting.

3. An attachment plug receptacle comprising 35 a molded two-part body made of insulating material; and a pair of mounting ears, one for each end of the receptacle, each having integral fingers bent at substantially a right angle to the general plane of the plate and extending in opposite directions relative to each other, adapted to slidably fit apertures provided therefor in the two body parts, thereby serving to locate the two body parts relative to each other.

4. An attachment plug receptacle comprising 45 a two-part body, upper and lower, made of insulating material; and a pair of mounting ears, one for each end of the receptacle, each having a pair of integral upturned fingers adapted to slidably fit a pair of apertures provided therefor 50 in the upper body part, and having a single similar integral downturned finger adapted to slidably fit an aperture provided therefor in the lower body part.

5. An attachment plug receptacle comprising 55 a two-part body, upper and lower, made of insulating material; a pair of connecting plates, each having a straight section lying between the upper and lower body parts to be partially located thereby and a section for connection to an outlet box or the like, and having oppositely extending integral fingers at substantially right angles to the straight section entering suitable apertures in the body parts to further locate the connecting plate and holding the straight section 65 of the plate from skewing and thereby spreading the body parts when pressure is applied to the body toward the outlet box upon which the plates are connected.

6. An attachment plug receptacle comprising 70 a two-part body, made of insulating material; means for holding said body parts together; a pair of plates for connecting the receptacle to an outlet box or the like, each plate having oppositely extending integral fingers at substan- 75

tially right angles to the general plane of the plate adapted to enter suitable apertures in the body and positively prevent skewing movement of the plate after the body parts are secured 5 together by said means.

7. An attachment plug receptacle comprising a rectangular body of insulating material, having side and end walls, recessed from its upper face to provide only one longitudinally extending contact receiving cavity; a pair of contacts

adapted to stand on edge in said cavity; and each having a laterally offset terminal portion near its center adapted to enter cut-out portions of the side walls; means to hold the contacts from longitudinal shifting within the body; and transversely extending raised beads within the body, adapted to engage sides of the contacts for locating them relative to the side walls and for preventing transverse shifting.

ARTHUR C. GAYNOR. 10
